(57) **CLAIM**

The ornamental design for an autonomous vehicle seat, as shown and described.

DESCRIPTION

The present application is related to application Ser. No. 29/491,937, entitled Autonomous Vehicle Overall Interior; to application Ser. No. 29/491,870, entitled Autonomous Vehicle Storage Bin/Tray; to application Ser. No. 29/491,867, entitled Autonomous Vehicle Console; to application Ser. No. 29/491,885, entitled Autonomous Vehicle Control Buttons; and to application Ser. No. 29/491,889, entitled Autonomous Vehicle Go/Pull Over Button, each of which is filed concurrently herewith, the entire disclosures of which are incorporated by reference herein.

FIG. 1 is a front perspective view of an autonomous vehicle seat according to a first embodiment of our design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top elevation view thereof;

FIG. 7 is a bottom elevation view thereof;

FIG. 8 is a front perspective view of an autonomous vehicle seat according to a second embodiment of our design;

FIG. 9 is a front elevation view thereof;

FIG. 10 is a right side elevation view thereof; and,

FIG. 11 is a left side elevation view thereof.

Broken lines, including any stitching patterns, are environmental only and form no part of the claimed design.

Areas of the design shown with a stipple fill preferably have a color, illumination or shading that contrasts with a color, illumination or shading of the non-stipple filled areas.
